[57] **CLAIM**

The ornamental design for a food processor attachment housing, as shown and described.

DESCRIPTION

FIG. 1 is a perspective view as seen from the top, front and left side of a food processor attachment housing showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIGS. 2, 3, 4, 5, and 7 are used for illustrative purposes only and form no part of the claimed design.

The broken line showing of a collar in FIGS. 1 through 5 and 7 is for illustrative purposes only and forms no part of the claimed design.
